UNITED STATES PATENT OFFICE.

PAUL W. NAPIERALA, OF DETROIT, MINNESOTA.

HAME-FASTENER.

No. 899,890.

Specification of Letters Patent. Patented Sept. 29, 1908.

Application filed January 7, 1907. Serial No. 351,149.

To all whom it may concern:

Be it known that I, PAUL W. NAPIERALA, a citizen of the United States, residing at the city of Detroit, in the county of Becker and 5 State of Minnesota, have invented new and useful Improvements in Hame-Fasteners, of which the following is a specification.

My invention relates to new and useful improvements in hame fasteners and more 10 particularly to a fastener for the top of the hame and my object is to provide means for securing the upper ends of the hames to opposite sides of the collar and in position to prevent the collar from pinching or otherwise 15 injuring the neck of the animal.

A further object is to provide means for adjustably securing the hames to the collar.

A still further object is to provide means for holding the separated ends of the collar 20 in a closed position and a still further object is to provide means for limiting the separating movement of the ends of the collar when the collar is being removed from the neck of an animal.

25 Other objects and advantages will be hereinafter referred to and more particularly pointed out in the claims.

In the accompanying drawings which are made a part of this application, Figure 1 is 30 a side elevation of my improved fastener as applied. Fig. 2 is a perspective view of a buckle used in my improved fastener. Fig. 3 is a modified form of buckle. Fig. 4 is a plan view of the connecting strap, and Fig. 5 is a section of a hame showing the form of 35 eye as used with the buckle shown in Fig. 3.

Referring to the drawings in which similar reference numerals designate corresponding parts throughout the several views, 1 indicates the hames, which may be of the usual 40 or any preferred construction and adapted to be secured together at their lower ends in any preferred manner, while the upper ends of said hames are provided with eyes 2, and 45 3 indicates the collar to which the hames are to be secured, said collar being constructed in the usual manner and separated at its upper end, so that the ends of the collar may be readily moved apart to remove the collar 50 from the neck of the animal.

Secured to the collar 3 in any preferred manner, as by means of loops 4, are buckles 5, said buckles being located adjacent the separated ends of the collar and having 55 curved portions 6 adjacent their upper ends, which curved portions terminate in a cross

bar 7, said bar being entered through the loop 4 to retain the buckle in place on the collar.

Extending across the buckle, substantially at the axial center of the same and parallel with the bar 7, is a cross bar 7^a, at the longitudinal center of which is formed a curved tongue 8, while at the lower end of the buckle is formed a cross bar 8^a, which is 65 likewise parallel with the bars 7 and 7^a.

Secured to the cross bar 8^a, is a stem 9, which is provided at its outer end with a lateral extension 9^a, said extension being substantially at right angles to the axis of the 70 stem, while the outer end of the extension terminates in a terminal 10, the free end of which is curved upwardly and out of alignment with the stem 9, the stem and extension forming a hook, which is adapted to engage 75 an eye in the hames respectively and removably secure the hames to the collar, the curved end of the terminal 10 extending out of alignment with the eyes and preventing the hames from casually leaving the hooks. 80

In order to secure the upper ends of the collar 3 together, after the collar has been placed in position on the neck of the animal, I provide a strap 14, which may be constructed in any preferred manner and of any 85 suitable width, the opposite ends of said straps being provided with a plurality of openings 15, which are adapted to be engaged by the tongues 8 of the buckles, the longitudinal center of the strap being located 90 centrally over the neck of the animal, whereby, when the ends of the collar are drawn together, they will move towards each other in unison, thereby equalizing the pressure of the collar on opposite sides of the neck of the 95 animal.

By securing the hames to the buckles at the upper end of the collar, the drawing together of the lower ends of the hames will give an outward pull to the upper ends of the 100 hames, thereby leaving the upper end of the collar free from pressure and snugly fitting the neck of the animal, thus obviating any abrasions at the point where the collar extends over the neck of the animal. 105

That portion of the strap 14 extending immediately over the meeting point of the ends of the collar, may be made any desired width and is preferably of such a width as to form a shield for the collar at this point and, thereby, prevent water or snow from coming in contact with the neck of the animal im-

mediately below the meeting ends of the collar.

In assembling the parts together, the end of the strap 14 is placed over the cross bars 5 7^a and below the cross bars 8^a, the hooks 8 on the cross bars 7^a, being entered through one of the openings 15 in the end of the strap and, by swinging the buckles upwardly, the 10 ends of the collar may be separated a sufficient distance to allow the collar to freely pass over the head of the animal and onto its neck and after the collar has been properly placed in position, the buckles are swung downwardly and the ends of the collar drawn 15 together, when the extension 9^a of the hooks and terminals 10 thereon are introduced through the eyes 2 on the hames and the lower ends of the hames then secured together and, if it is found that the collar does 20 not exactly fit the neck of the animal, the tongues 8 may be introduced into different holes in the strap 14, the adjustment being such that the collar may be made to fit the necks of different animals.

25 In attaching the hames to the hooks, the lower ends of the hames are swung outwardly until the eyes in the hames are in position to receive the terminals 10, the eyes being of sufficient width to allow the terminal and its 30 curved end to pass and, by moving the hames inwardly, the terminals pass through the eyes and beyond the forward face of the hames when, by moving the lower ends of the hames inwardly, the curved portions of 35 the terminals are moved out of alignment with the eyes, and, thereby, preventing the casual removal of the hames until the eyes are again brought in registration with the terminals.

40 In some instances, instead of forming the extension 9^a at right angles to the stem 9 and providing the terminal therefor, the terminal may be dispensed with and the extension curved upwardly and rearwardly over the 45 stem 9 and, when this form of hook is provided, the eyes are placed on the inner face of the hame and said eyes are formed by providing cavities 11 on the inner face of the hame, over which is secured plates 12, said 50 plates having openings therein, across which extend bars 13, the hooks on the buckles being adapted to engage said bar and secure the hames to the buckles. This form of buckle is also employed in connection with 55 the usual form of iron hames, having loops at their upper ends for receiving straps.

It will thus be seen that I have provided a very cheap and economical means for holding the upper ends of the hames in engagement 60 with the collar and that the hames may be adjusted thereon as desired. It will further be seen that I have provided means for holding the collar in position on the neck of an animal without causing the collar to bind the 65 neck of the animal or otherwise cause abra-

sions thereon and it will likewise be seen that said collar may be readily removed without completely releasing the upper ends thereof and, by limiting the separated or outward movement of the upper ends of the collar, 70 said collar will not become broken or torn apart at its lower end.

What I claim is:

1. In a device of the class described, the combination with a hame having an eye on one face thereof; of a collar, buckles secured to said collar, said buckles each having a hook at the lower end thereof adapted to engage the eye on the hame and a strap having openings therein adapted to be engaged by 75 tongues on said buckles, whereby said parts 80 will be secured together.

2. In a hame fastener, the combination with a collar having buckles secured thereto, said buckles having tongues thereon and 85 hooks at the lower ends thereof; of hames having eyes thereon adapted to be engaged by said hooks and a strap adapted to be passed over said collar, said strap having 90 openings therein adapted to be engaged by the tongues on said buckles, whereby said parts 95 will be secured together.

3. In a hame fastener, the combination with a collar having buckles secured thereto, said buckles having downwardly curved 100 tongues midway of the body and upwardly curved hooks at the lower ends thereof; of a hame having means thereon adapted to be engaged by said hooks and a strap adapted to pass over the collar, said strap having 105 openings therein adapted to be engaged by the tongues on the buckles, whereby said 110 hame will be securely fastened.

4. In a hame attachment, the combination with a collar, of buckles hingedly secured thereto, curved tongues on said buckles, means extending between said buckles adapted to engage said tongues and secure the ends of the collar together, hames for 115 said collar and means extending from the buckles adapted to engage said hames and hold the same in position on the collar.

5. The combination with a collar; of buckles pivotally mounted on said collar, curved tongues on the buckles, a strap extended between the buckles, said strap having 120 openings therein to engage said tongues and hold the collar in its closed position, hames for said collar and means to removably attach the hames to the buckles.

6. In a hame fastener, the combination with a collar; of buckles secured to said collar, a strap extending over the upper ends of the collar and having a plurality of openings therein, means on the buckles adapted to enter said openings and hold the collar in a closed position when the buckles are adjusted in one position and limit the outward movement of the ends of the collar when the buckles are turned in opposite positions,

hames for said collar and means on the
buckles to engage and removably secure said
hames thereto.

7. In a hame fastener, the combination
5 with a collar; of hames adapted to fit said
collar, each hame having an eye thereon,
buckles secured to said collar, hooks on said
buckles adapted to enter said eyes and sup-

port the hames on the collar and means at
the outer ends of said hooks to prevent the 10
casual removal of the hames from the hooks.

P. W. NAPIERALA.
